DUST MOP CLEANER

Henning R. Larson, Worcester, Mass.

Application February 5, 1940, Serial No. 317,342

5 Claims. (Cl. 15—104)

This invention relates to machines for removing dust and dirt from mops used in dusting floors and for other cleaning. In city apartments and other thickly settled localities, it is often difficult to find an available place where such a mop can be shaken or beaten without disturbing other parties by the flying dust and dirt.

It is the general object of my invention to provide an improved portable machine by which a dust mop can be readily rotated within a closed casing for a beating operation. I also provide an improved bearing support for the rotated mop, and a conveniently removable receptacle to receive the dust and dirt.

My invention further relates to arrangements and combinations of parts which will be herein-after described and more particularly pointed out in the appended claims.

A preferred form of the invention is shown in the drawings, in which

Fig. 1 is a front elevation of my improved machine;

Fig. 2 is a side elevation thereof;

Fig. 3 is a detail sectional view, taken along the line 3—3 in Fig. 1;

Fig. 4 is a sectional front elevation, taken along the line 4—4 in Fig. 2;

Fig. 5 is a sectional plan view, taken along the line 5—5 in Fig. 4;

Fig. 6 is a partial sectional side elevation, taken along the line 6—6 in Fig. 5;

Fig. 7 is a partial sectional side elevation, taken along the line 7—7 in Fig. 1;

Fig. 8 is a detail sectional view, taken along the line 8—8 in Fig. 7;

Fig. 9 is a detail plan view, looking in the direction of the arrow 9 in Fig. 7;

Fig. 10 is a detail sectional side elevation, taken along the line 10—10 in Fig. 8;

Fig. 11 is a diagrammatic view showing the operation of the machine in cleaning a mop;

Fig. 12 is a partial side elevation of a mop-engaging cross bar and its supporting means;

Fig. 13 is an end elevation, looking in the direction of the arrow 13 in Fig. 12;

Fig. 14 is a detail sectional view, taken along the line 14—14 in Fig. 4;

Fig. 15 is a side elevation of a dust-container; and

Fig. 16 is a detail sectional view, taken along the line 16—16 in Fig. 1.

Referring to the drawings, my improved dust mop cleaner comprises a casing 20 and a cover 21 hinged together at 22 (Fig. 2). The casing 20

supports an inner sheet metal trough 24, the upper portions of which are permanently secured to the side and end walls of the casing 20 by soldering or welding, and the lower portions of which are spaced inwardly from the side and end walls, 5 as clearly shown in Figs. 4 and 6.

The sides and ends of the trough 24 converge downwardly toward an open rectangular delivery portion 25 through which dust and dirt is discharged to a removable dust-container 27. The container 27 preferably has a canvas casing 28 enclosing the container and extending upwardly beyond the container, as clearly shown in Fig. 15. This upper portion of the casing 28 is provided with a gathering string or cord 29 by which it may be firmly secured around the delivery portion 25 of the trough 24. When it is desired to empty the container 27, the cord 29 is loosened and the container is removed through a door 30 (Fig. 1) in the front of the casing 20. A latch 31 holds the door normally closed.

A cross bar 32 (Figs. 6, 12 and 13) is secured to the upper ends of slotted plates 33 in any convenient manner, as by screws 34. The plates 33 are adjustably secured to the ends of the delivery portion 25 of the trough 24 by clamping bolts 36 (Figs. 6 and 12). By loosening the bolts 36, the cross bar 32 may be adjusted at any desired height to engage a mop M of a particular size.

The casing 20 is supported on swivel wheels or rollers 40 (Figs. 1 and 2) and is provided with end handles 41 and a stirrup strap 42 (Fig. 1). The wheels 40 and handles 41 permit the machine to be readily drawn about from place to place, and the stirrup strap 42 conveniently receives the foot of the operator, thus enabling him to hold the machine from movement on its wheels 40 during a mop-shaking operation.

The casing 20 and cover 21 are reenforced and overlap at their adjacent edges, as shown in Fig. 16, and the joint between these parts is preferably covered by a packing 43 which prevents the escape of dust and dirt from the machine.

The casing 20 has a mop-handle-receiving opening 50 (Figs. 1 and 8) in its upper front edge portion, together with a coacting and downwardly extending rectangular slot 51. The cover 21 has a corresponding segmental opening 52 overlying the mop handle when a mop is supported in 50 the machine.

The mops cleaned in this machine commonly comprise a wire or metal cross frame 60 (Fig. 11) to which is secured a multiplicity of elements 61, such as fibre, threads or cords. The cross frame 53

60 has a threaded cup 62 secured thereto, which cup is adapted to receive the threaded outer end 63 (Fig. 10) of a bearing rod or stud 64. Displacement of the brush on the stud during the 5 cleaning operation may be prevented by inserting a locking screw 65 through the parts 62 and 63.

The bearing stud 64 (Fig. 10) is rotatable in sleeves 66 and 67, which sleeves are secured together by a connecting member 68. The sleeves 10 66 and 67 are loosely mounted on the stud 64 at each side of a pinion 69 which may be pressed on the stud 64 or may be secured by a crosspin 70. A short tubular member 71 is fixed to the outer 15 end of the sleeve 67 and receives the end of the mop stick 72, which may be secured therein by screws 73.

With this construction, it will be seen that the stick 72, the tubular member 71, the sleeves 20 67 and 66 and the connecting member 68 may remain stationary and thus provide an elongated bearing for the stud 64 which supports the mop M and which is rotated by a driving connection to the pinion 69.

A bracket 75 (Figs. 7 and 9) is bolted to the 25 casing 20 below the openings 50 and 51 and extends inward and upward to provide an inner support 76 for the sleeve 66. At its inner end, the bracket 75 is provided with ears 77 to prevent transverse displacement of the mop during 30 cleaning. The bracket 75 is also provided with a slot 78 to receive the connecting member 68 as shown in Fig. 7, said member 68 also extending out through the lower portion 51 of the opening in the casing 20.

35 A hand lever 80 is pivotally mounted between bearing plates 81 (Fig. 14), which plates in turn are secured to the front wall of the cover 21 by bolts 82 (Fig. 1). The handle 80 extends upward through a slot 83 (Fig. 3) in the top of the 40 cover 21 and is conveniently positioned to be grasped and operated above said cover. A cloth pouch or packing member 84 is secured within the cover 21 and is closely engaged with the handle 80 to prevent escape of dust through the slot 83.

At its lower end the lever 80 is formed as a 45 segment gear 85, the teeth of which engage the pinion 69 when the cover is closed. Handles 90 and 91 provide convenient means for opening the 50 cover 21 and a chain 92 (Fig. 2) limits such opening movement.

Having described the details of construction of my improved mop cleaning machine, the use 55 and method of operation thereof will be readily apparent.

When the cover 21 is raised, a mop M may be inserted in the casing 20, with its bearing parts firmly supported as shown in Fig. 7. The cross bar 32 is then adjusted, if necessary, to the right 60 height for the particular style or type of mop to be cleaned. The cover is then closed, causing the segment gear 85 to engage the pinion 69, and the mop is then rapidly rotated, first in one direction and then in the other, by rocking the handle 80. At the same time the operator places 65 his foot on the stirrup strap 42 and thus pre-

vents bodily movement of the machine, which might otherwise attempt to follow the movements of the handle. Also, the operator may use his other hand to grasp the mop stick 72, which stick does not rotate. 5

The mop rotates on the elongated bearings of the stud 64 in the sleeves 66 and 67, and when thus rotated, the threads or cords 61 fly outward by centrifugal force and strike the bar 32, which effectively removes the dust and dirt therefrom. 10 This dislodged material thereafter collects in the receptacle 27 and may be removed. The mop is thus quickly and easily cleaned without the escape of dust or dirt from the machine and is immediately ready for further use. 15

Having thus described my invention and the advantages thereof, I do not wish to be limited to the details herein disclosed, otherwise than as set forth in the claims, but what I claim is:

1. In a mop cleaning machine, a casing, a cover 20 hinged thereto, a mop-stick, means to rotatably support a mop on said mop-stick, means to horizontally support said mop-stick and rotating means between said casing and cover and to hold said stick from rotation, and manual means to 25 rotate said mop on said stick while said stick is held stationary.

2. In a mop-cleaning machine having a casing and a manually operated segment gear rotatably mounted thereon, that improvement 30 which comprises a mop rotatably mounted on a mop-stick, a pinion on said mop engaged and rotated by said segment gear when said mop is positioned in said machine, and means to firmly support said mop-stick in said casing at both 35 sides of said pinion.

3. In a mop-cleaning machine, a mop, a bearing stud for said mop, spaced bearing sleeves for said stud, a pinion fixed on said stud between said sleeves, means to rigidly connect said spaced sleeves and to secure said sleeves to a mop-stick, and manual means to rotate said pinion and mop. 40

4. In a mop-cleaning machine, a casing, a mop-stick, means to rotatably support a mop on said 45 mop-stick, means to horizontally support said mop-stick and rotating means in said casing, and a bracket secured within said casing and projecting inward therefrom to engage and support the inner end of said stick, said bracket having 50 a slot positioned to receive a device on said mop-stick so constructed and arranged that said stick is held from rotation.

5. In a mop-cleaning machine, a casing, a mop-stick, means to rotatably support a mop on said 55 mop-stick, means to horizontally support said mop-stick and rotating means in said casing, and a bracket secured within said casing and projecting inward therefrom to engage and support the inner end of said stick, said bracket having 60 a slot positioned to receive a device on said mop-stick so constructed and arranged that said stick is held from rotation and having spaced ears to prevent lateral displacement of the inner end 65 of said stick.

HENNING R. LARSON.
